COMBINED CLIP AND CLAMP FOR SURGICAL TUBING OR THE LIKE

Leonard W. Lock, Sittingbourne, England, assignor to
Abbott Laboratories, North Chicago, Ill.

Filed June 29, 1972, Ser. No. 267,280

Term of patent 14 years

Int. Cl. D8—07; D24—02; D7—05
U.S. Cl. D8—259

FIG.3

FIG.2

FIG.1

FIG.4

FIG.5

FIG. 1 is a front plan view of a combined clip and clamp for surgical tubing or the like showing my new design;

FIG. 2 is a side plan view of the clip portion;

FIG. 3 is a top plan view;

FIG. 4 is a side plan view of the clamp portion; and

FIG. 5 is a bottom plan view.

I claim:

The ornamental design for a combined clip and clamp for surgical tubing or the like, substantially as shown and described.
